PROCESS FOR PRODUCING DEHYDRO-PERILLIC ACID

William G. Van Beckum, Longview, Wash., assignor to Weyerhaeuser Timber Company, Longview, Wash., a corporation of Washington

Application June 17, 1948, Serial No. 33,638

6 Claims. (Cl. 260—124)

1

This invention relates to a process for the production of an organic acid, and more particularly pertains to a process for the production from lignocellulose materials of an organic acid heretofore identified and known as dehydroperilllic acid. The process of the invention is particularly applicable to the production of the said acid as a by-product of a commercially feasible process for the production of lignin from aqueous alkaline extracts resulting from the treatment of fiber derived from certain species of woods with a dilute aqueous solution of an alkali metal hydroxide. This application is a continuation-in-part of abandoned application Serial No. 602,916, filed July 2, 1945.

The properties of the acidic compound which is a product of the process of the invention indicate that it may be an analogue of perillic acid, differing therefrom in that it contains one additional double bond in its molecular structure. It has, therefore, been tentatively named dehydroperilllic acid (cf. Journal of the American Chemical Society, v. 55:3813-9 (1933)). The relationship between the two compounds is clearly evident from the following structural formulas:

Formula I

Perillic acid

Formula II

Dehydroperilllic acid

It is with a process for the production on a commercial scale of the compound, herein termed dehydroperilllic acid, and having the probable structure illustrated above in Formula II, that the present invention is concerned.

Dehydroperilllic acid may be produced in accordance with the process of the invention from almost any lignocellulose material in which it is contained, either as such or in a form which is convertible thereto under the herein described conditions of treatment. Certain varieties of wood, such as western red cedar, are especially suitable sources.

2

When wood is used as a source material for the production of dehydroperilllic acid in accordance with the herein described process, it is preferably first reduced to fibrous form by mechanical or other methods which do not subject the wood to the action of added chemicals other than water. This reduction is carried to the point where it results in the conversion of the wood substance to fibers physically consisting substantially of ultimate fibers and opened-up bundles of ultimate fibers and constitutionally consisting primarily of cellulose, lignin, and polysaccharides-other-than-cellulose, herein frequently referred to merely as "polysaccharides," these three constituents being present in mutual ratios in the range of contents falling between that characterizing the raw wood from which the fiber is derived and that characterizing the water-insoluble content of the raw wood from which the fiber is derived. Fiber containing cellulose, lignin, and polysaccharides-other-than-cellulose in the range characterizing the water-insoluble content of the raw wood from which the fiber is derived is exemplified by raw wood fiber which has been so treated with water as to extract the water-soluble constituents and leave as a fibrous residue the water-insoluble content of the wood. The production of such fiber from woods such as western larch is of particular interest, since these woods contain high percentages of water extractable substances, e. g. about 23% in the case of western larch. It may, therefore, be commercially desirable in the case of these woods to extract them with water in order to isolate as commercial products the water-soluble fraction of the wood substance. A fiber residue is thus obtained which may be employed to advantage as a raw material for the fractionation process of the instant invention.

The wood fibers to which the process of the invention may satisfactorily be applied may be produced, for example, by the method described in United States Letters Patent No. 1,913,607 to McMillan. This patent describes a mechanical defibering process entirely free from chemical action, which comprises combing out substantially ultimate fibers from wood by contacting logs of wood with high speed rotary radial elements such as pointed pins projecting from an axle, like bristles. Fiber produced by this process is herein referred to as McMillan fiber, or pin fiber.

Wood fiber suitable for use in the process of the present invention may also be prepared by the method described in the United States Letters Patent No. 2,008,892 to Asplund. In this method wood substance is defibered by mechanically reducing the wood while simultaneously applying sufficient steam pressure to soften the lignin in the middle lamella, thus permitting easy defibration of the softened wood. The fiber re-

sulting from this practice in efficient operation of the commercial Asplund machine is termed herein normal Asplund fiber, or normal defibrator fiber. It is prepared, for example, by reducing wood while exposing it for about one minute to high pressure steam at a temperature sufficient to effect the desired softening.

Other processes may be employed for reducing wood substance to said ultimate fibers or opened-up bundle form. The wood substance may be affected by steam at any time or times before, during or after such defibration. Action by steam should be such as to avoid any substantial gasification of the wood substance which thus leads to loss or decomposition of wood substance, usually with the formation of furfural, as well as to altered proportions of the three primary constituents, and unduly altered forms of said constituents. The fibers resulting from processes involving both defibering and steaming, which includes those resulting from the Asplund process, differ from the raw wood in that their water-soluble content has been to a greater or lesser degree increased by the action of the steam. In the case of normal Asplund aspen fibers made in about one minute at about 128 pounds steam pressure, the increase in water-soluble content is 4% to 6%.

Other methods for producing fibers from wood substance may also be used, provided said methods do not subject the wood to the action of added chemical agents other than liquid water or steam.

It has been discovered that dehydroperillie acid may be obtained by subjecting lignocellulose materials which contain it to the action of a dilute aqueous solution of a basic-acting compound of an alkali metal, separating the treated material from the resulting solution, and isolating from the said resulting solution its content of dehydroperillie acid.

More specifically stated, dehydroperillie acid is obtained from lignocellulose materials, e. g. wood fiber, in accordance with the process of the present invention, by treating such materials with an aqueous alkaline reagent preferably comprising a weak aqueous solution of an alkali metal hydroxide, e. g. sodium hydroxide, at an elevated temperature for a time sufficient substantially to exhaust the extracting action of the alkali, thereby forming a solution comprising dehydroperillie acid, polysaccharides-other-than-cellulose, and lignin, and leaving a fibrous residue, separating the said solution from the said residue, and concentrating and acidifying the said solution in order to separate therefrom its dehydroperillie content.

A specific embodiment of the invention for obtaining dehydroperillie acid from lignocellulose material is illustrated in the drawing. In accordance with the procedure therein outlined, lignocellulose material, e. g. the fiber of western red cedar, indicated at 7, containing substantially all of the water-insoluble content of the wood from which the fiber is derived, and prepared by the hereinabove referred to Asplund, McMillan or other processes, and physically consisting substantially of ultimate fibers and opened-up bundles of ultimate fibers and constitutionally consisting primarily of cellulose, lignin, and polysaccharides-other-than-cellulose, said three constituents being present in mutual ratios in the range of contents from those characterizing the raw wood from which the fiber is derived to those characterizing the water-insoluble content of the said raw wood from which the fiber is derived, is treated at 8 with an alkaline reacting compound of alkali-metal. The alkaline reagent employed is

typically exemplified by sodium hydroxide, e. g. a $\frac{1}{4}$ normal solution of alkali-metal hydroxide, in a total amount with respect to fiber sufficient to maintain an extracting alkalinity during the operation. This treatment is preferably carried out at atmospheric pressure and at about the boiling point of the said solution. The time of treatment is variable depending upon the type of wood being treated and the other conditions of the treatment, but, in general, may be up to about two hours, or such time as shows the extraction to be substantially complete. This treatment extracts from the wood substance the dehydroperillie acid as well as a substantial proportion of the lignin and polysaccharides-other-than-cellulose content and leaves a fibrous residue. The reacted mass is extracted at step 10 to separate the soluble matter from the thus treated fiber.

Step 8 may be practiced by a batchwise procedure or by a counter-current or recycling procedure as hereinafter more fully discussed. Water is usually employed as the solvent in step 10, but the water may also be admixed with other materials in order to contribute specific properties to the solvent or for specific purposes. Water alone, or with such other materials admixed therein, is herein referred to as an aqueous solvent. Steps 8 and 10 may be efficiently combined when an aqueous solution of sodium hydroxide is used, but when moist wood fiber is treated with solid sodium hydroxide, or with solutions so concentrated as to amount to syrups, the separate aqueous extraction step 10 will be necessary.

The mass or slurry, with the treated fiber in aqueous suspension, is next filtered at step 12, or otherwise processed to separate the treated lignocellulose residue 13, herein arbitrarily designated as Fiber I, from the soluble matter in the filtrate or solution 15, arbitrarily herein designated Extract I, which contains the dehydroperillie acid, lignin and the other organic materials including the polysaccharides-other-than-cellulose.

After separation of the said residue 13 from the extract 15, the said extract is treated for isolation of its dehydroperillie acid content. It is first neutralized at step 16, preferably by adding sulfuric acid, thereby reducing the pH from an original value of about 10 to one of about 7. The solution as thus acidified is then conditioned for precipitation at step 18. This conditioning may take one of two forms, or a combination of both — by either the removal of water of solution, step 20, or by the addition of inorganic salts, step 22. Both treatments have in common the fact that they result in the concentration of the solution to a point at which completion of the lignin precipitation is effected. The precipitated lignin is then filtered at step 24 and recovered at 25 as product lignin 1-a.

It is desired at this point to elaborate on step 18 of conditioning the solution for precipitation of the lignin, especially since this same step is generally applicable at other steps in the process, or in other sequences, to the separation of the other lignin products at other pH ranges. While some precipitation of lignin may occur by virtue of establishment of the pH range for separation of the lignin product concerned, the separation of the lignin in this manner is not sharp, and it is advisable to condition the solution in order to effect the complete precipitation of all the lignin which will separate at the particular pH range. After neutralization, the solution may be concentrated by evaporation, which step, if practiced, is included in step 18. The concentration is con-

tinued to a point where the lignin content is precipitated in substantial amount. The solution is preferably maintained neutral during the concentration step by the addition of acid as necessary. It will be obvious that the need for concentration by removal of water will depend upon the usage of alkali and the concentration of the alkali in the solution 15. The more the salt content formed by the interaction between the alkali and the acid, the less will be the extent to which the removal of water needs to be continued. It will be further appreciated in this connection that steps 16 and 18 are more or less interdependent and that either step may be performed first; that is, either the removal of water or the addition of the salt may precede acidification. It is generally more advantageous, however, for step 18 to follow step 16, because, in this manner, full advantage can be taken of the salts formed by the neutralization of the alkali present.

When the conditioning of the solution for precipitation is to be accomplished by the addition of inorganic salts as at 22, sodium acid sulfate is preferably used, and is added until the solution is near saturation with respect to this compound. At this point, precipitation of lignin 1-a can be expected to be substantially complete. The neutral, concentrated solution containing undissolved lignin, preferably at room temperature, is filtered at 24, thereby separating lignin 1-a, designated at 25, in the solid form.

The filtrate 26, which contains the dehydroperillic acid in salt form together with the polysaccharides-other-than-cellulose and additional lignin products, is next acidified to a pH of about 5 at step 27. This causes the precipitation of the dehydroperillic acid together with an additional lignin product. The resulting mixture is then warmed to a temperature of about 65° C. at step 28 in order to coagulate the lignin product and effect its separation from the dehydroperillic acid. Upon cooling, the coagulated lignin product is to be found in large part settled out on the bottom of the containing vessel, while the supernatant liquid contains suspended crystals of dehydroperillic acid together with a fine suspension of lignin product particles. Since the particle size of the dehydroperillic acid crystals is substantially greater than that of the suspended lignin product particles, it is possible to effect the separation thereof, as by decanting the supernatant liquor from the coagulated lignin product remaining in the vessel, the said supernatant liquor being passed through a filtering means whereof the mesh size is such as to permit passage of the fine particles of suspended lignin product, but to retain the larger dehydroperillic acid crystals. This is represented at step 29. This results in the formation of a filtrate 31, which contains lignin products in aqueous solution and in suspension, together with polysaccharides-other-than-cellulose in aqueous solution, and, as a solid product in cake form, the crude dehydroperillic acid 32. This acid may be refined, as by washing with cold water, at step 33 to give a purified dehydroperillic acid product 34, while the filtrate 31 may be processed to isolate valuable polysaccharides-other-than-cellulose and lignin products therefrom.

It will be apparent that the operating conditions as described in the preferred embodiment may be varied as desirable or necessary when processing different types of lignocellulose materials or employing a range of reagent concentrations. For example, various alkaline materials

may be employed in the treating step 8. Suitable alkaline materials include in general the hydroxides of the alkali metals as well as those alkali metal compounds which, being salts of strong bases and weak acids, undergo hydrolysis in aqueous medium to form the alkali metal hydroxides, or their equivalent in alkali metal ions and hydroxyl ions. Such compounds are, therefore, the basic-acting compounds of the alkali metals, i. e. of lithium, sodium, potassium, rubidium, and caesium. The hydroxides of this group of metals, especially sodium hydroxide, are preferred reagents for effecting the herein described extraction, although the carbonates, e. g. sodium carbonate, may also be used.

Similarly, the operating conditions of the extraction step, wherein the lignocellulose material is treated with a dilute aqueous solution of alkali, may be varied within limits to suit the particular lignocellulose material being treated. It is the teaching of the invention, however, and often critical to its success in practice, to use and maintain operating conditions and reagents of such a mild character as to effect the fractionation of the lignocellulose materials without causing substantial or drastic changes in the composition of the constituents thereof. Thus, it is preferred to use a relatively weak solution of alkali, i. e., a solution which contains sufficient alkali to be about $\frac{1}{4}$ normal with respect thereto. A preferred solution for effecting the extraction is a 0.6% solution of sodium hydroxide.

Usages of alkali largely in excess of those necessary to obtain the desired fractionation are also avoided. The total amount of alkali metal hydroxide used is usually based upon the weight of fiber treated. Thus, for example, a usage of 15% sodium hydroxide signifies that 15 parts by weight of sodium hydroxide is used to extract 40 100 parts of dry fiber.

Where a mixing procedure is employed in the extraction with alkali metal hydroxide, the consistency of the reaction mixture (i. e. the weight of fiber per 100 parts by weight of solution) is maintained at a level such as to afford ease of manipulation and thoroughness of treatment. The optimum consistency is obviously dependent upon many factors, principally upon the method of handling the fiber mixture. Thus, varying 45 consistencies may be used, depending upon whether the fiber is treated batchwise, or continuously, as in counter-current operation.

It will be apparent that concentration, usage and consistency are interrelated factors and that variations in one will affect the others. Thus, when the concentration and usage are varied, the consistency also changes. Various combinations of these variables are possible, the practical limiting factors being, as disclosed above, the desirability of keeping the operating conditions relatively mild, and also of providing consistencies such as to favor ease of handling, drying, processing and relatively complete separation of extract from treated material. A representative 55 combination of these variables suitable for use in extracting many woods in fibrous form comprises the use of an aqueous sodium hydroxide solution having a concentration of 0.6% by weight sodium hydroxide in an amount equal to 15% by weight 60 of the fiber treated, whereupon the consistency of the mixture will be about 4%.

As stated hereinabove, the alkaline extraction is carried out at a temperature which is preferably about the boiling temperature of the mixture at normal atmospheric pressure. In ordinary

opération where the process is carried out at normal atmospheric pressure in open vessels, and where the described dilute solutions are employed, the temperature of operation will be about 100° C.

Treating times of up to about two hours may be employed. In most instances, relatively little advantage obtains from treating durations of more than about one hour.

Largely for reasons of economy and efficient operation, it is usually preferred, when batch-wise extraction is being practiced, to recycle the alkaline solution used in the extraction. In this manner the dehydroperillic acid concentration is built up in the alkaline solution to a point where the said solution becomes an increasingly valuable source thereof. Since some of the alkali is consumed by reaction with the wood substance during the extraction process, it is desirable to add a further quantity of alkali before treating fresh wood fiber. In the case of woods such as western red cedar extracted at 4% consistency with a 0.6% solution of caustic soda, about 60% replacement of the original caustic alkali usage after each extraction is sufficient to fortify the solution to the desired degree, e. g., to a concentration of about 0.6% in the case of caustic soda. Although the number of times an alkaline solution which has been thus fortified may be used for the extraction of raw wood is variable depending largely upon the nature of the wood, it has been observed that extracting eight times in the above described manner and fortifying the resulting extract with additional alkali before each extraction results in the production of an alkaline extract rich in dehydroperillic acid, lignins and polysaccharides-other-than-cellulose and, at the same time, leaves a fiber residue of useful composition and properties.

Recycling, or its equivalent operation, may be profitably practiced until the contribution of dehydroperillic acid of each new batch of fiber equals the amount of dehydroperillic acid retained by the fibers upon separating the fibers and the extract. Obviously, this involves many factors including the amount of dehydroperillic acid contributed by each successive batch of fiber as well as the efficiency of the mechanical step of effecting the separation.

Similarly, the operating procedures hereinabove outlined for the processing of the aqueous alkaline extract resulting from the treatment of the lignocellulose material with a dilute aqueous solution of an alkali-metal hydroxide may be varied within limits. It is a primary objective of the procedure, however, to provide conditions which will achieve the difficult function of separating the desired dehydroperillic acid product in a relatively pure form, uncontaminated by substantial quantities of the other constituents of the complex extract from which it is isolated, i.e. uncontaminated by polysaccharides-other-than-cellulose, mineral salts such as sodium sulfate, and, particularly, lignin. Thus, although it may be possible in some cases to separate the dehydroperillic acid from the extract without the prior separation of lignin 1-*a*, as by acidification of the said extract directly to a pH of about 5, followed by concentration to the desired degree and separation of the dehydroperillic acid from the precipitated lignin, it has been found that a more sharply defined separation of lignin from dehydroperillic acid and a purer product are obtained when the extract is freed from some of the lignin products, i. e., lignin 1-*a*, before the sepa-

ration of the dehydroperillic acid is effected. Various acids may be used at step 11 for neutralizing the dehydroperillic acid-containing extract. Any of the common mineral acids such as sulfuric acid, phosphoric acid, or hydrochloric acid, as well as some of the organic acids, e. g. acetic acid, are suitable for this purpose. Sulfuric acid is a preferred member of this group.

The amount of acid used is likewise variable, and depends largely upon the alkalinity of the extract. In general, enough acid is employed to result in the formation of a substantially neutral solution, i. e. one having a pH of about 7.

As stated, the neutralized extract is preferably concentrated to a point at which lignin 1-*a* is insoluble, but at which the dehydroperillic acid, polysaccharides-other-than-cellulose, and inorganic salt content of the extract, principally sodium sulfate when caustic soda and sulfuric acid are used in the extraction and acidification steps, and some other lignin products are substantially soluble. There is thus removed from the extract a substantial amount of lignin products of relatively low acidity, thereby simplifying the separation of the dehydroperillic acid at a later stage. Although the point at which this desideratum is attained varies with the relative proportions of solvent and solutes and with other factors, when the proportions and operating conditions are substantially as given in the examples herein, it is preferred to concentrate the neutralized solution to about 12% of its original volume.

The acidification step indicated at 27 in the drawing, wherein the aqueous solution remaining after separation of lignin 1-*a* is acidified to a pH of about 5, is likewise subject to variation within limits. It is the general objective of this step to acidify the solution to a point at which the dehydroperillic acid, up to this stage of the procedure in the form of a water-soluble salt, is converted to the free acid, which is insoluble in cold water, without effecting the precipitation of lignin products in amount sufficient to make the separation of the dehydroperillic acid in a relatively pure state difficult, if not impossible. It has been discovered that acidification to a pH of between about 4 and 6 usually accomplishes this purpose, a pH of about 5 being a preferred value. The acidification may be effected using any suitable acid of sufficient strength to reduce the pH of the solution to the desired level. Sulfuric acid is a preferred reagent for this use.

Step 28 has for its general object the coagulation of the lignin products which, together with dehydroperillic acid, almost invariably precipitates upon acidification of the solution to pH 5. The desired coagulation may be secured by warming the suspension, for example to from about 55° C. to about 75° C., preferably about 65° C. This step causes a large part of the lignin product to aggregate and settle to the bottom of the containing vessel, thus leaving a supernatant liquid containing as suspended crystals the desired dehydroperillic acid, together with some finely dispersed lignin product, and dissolved inorganic salts and polysaccharides-other-than-cellulose. Upon cooling, a further quantity of dehydroperillic acid separates. During the process of cooling the dehydroperillic acid forms crystals which are considerably larger in size than are the suspended lignin product particles. They may, therefore, be separated therefrom by pouring the supernatant liquid through any suitable type of filter having a mesh size such that

the lignin product particles pass therethrough but the dehydroperilllic acid crystals are retained upon the filter. The desired separation is thus effected.

Purification of the crude dehydroperilllic acid, obtained as above, may be accomplished, as is indicated at step 33 in the drawing, by washing one or more times with a solvent comprising cold water. Alternatively, the purification may be effected by dissolving the dehydroperilllic acid product in a suitable solvent and recrystallizing it therefrom. Alternatively, also, it may be dissolved in an aqueous solution of a suitable alkali, such as sodium hydroxide, thereby forming an aqueous alkaline solution of the dehydroperilllic acid salt, as sodium dehydroperillate, which may be reprecipitated as the free acid in a relatively pure state by acidification of the solution to a pH of about 5. Sublimation affords another method of purification.

It is to be understood that the term "lignin product" is used herein to designate lignin products obtained by chemical treatment of lignocellulose materials, although it is recognized that the lignin thus produced may have been altered in form or properties to a greater or lesser degree by reaction with the chemicals with which it has been treated.

The process of the invention is illustrated by the following example, wherein the parts are expressed as parts by weight:

Example

Asplund western red cedar fiber, i. e. fiber prepared from the wood of the western red cedar by means of an Asplund defibrator, was extracted with a 0.6% aqueous solution of sodium hydroxide. A sufficient amount of this solution was used to provide a total sodium hydroxide content equivalent to 15% based on the dry weight of the raw wood fiber. This resulted in a reaction mixture having a consistency of about 4%, i. e. a mixture containing about 4 parts by weight of fiber per 100 parts of solution. The extraction was effected at the boiling temperatures of the solution at about normal atmospheric pressure for a duration of one hour. The fiber was then separated from the sodium hydroxide solution and washed with water for subsequent uses. The alkaline extract was fortified by the addition of caustic soda in an amount sufficient to build up the sodium hydroxide concentration to a level substantially that of the original solution. This required replacement of about 60% of the original sodium hydroxide. The fortified solution was then employed in the extraction of a further quantity of raw wood fiber. A total of eight extractions of raw wood fiber was carried out in this manner, replenishing the concentration of sodium hydroxide in the extracting solution after each extraction. This resulted in the production of an alkaline extract containing dehydroperilllic acid and other materials removed from the wood substance.

This alkaline extract, which had a pH of about 10, was then processed for the recovery of its dehydroperilllic acid content by neutralizing with sulfuric acid and concentrating by evaporation while adding further sulfuric acid as necessary to maintain the solution neutral. The solution was thus concentrated to about 12% of its original volume. It was then cooled and filtered. This resulted in the separation of lignin products 1-a.

The filtrate resulting from the separation of lignin 1-a was acidified to a pH of 5, thereby precipitating dehydroperilllic acid, together with a quantity of another finely divided lignin product. This mixture was heated to a temperature of 65° C., and then allowed to cool slowly. This caused most of the lignin product to coagulate and settle to the bottom of the containing vessel within a few hours. After this treatment, the liquid above the coagulated lignin product contained a fine dispersion of lignin product particles together with relatively large crystals of dehydroperilllic acid. It was decanted through a coarse filter, thereby effecting the separation of the dehydroperilllic acid. Purification of the latter was effected by merely washing on the filter with cold water.

The product as thus produced was a white, crystalline solid having a melting point of about 88° C. Color tests with ferric chloride reagent were negative, indicating that the product was not a phenol. The presence of at least one carboxyl group was indicated by the fact that the product was soluble in sodium bicarbonate to give a solution from which it could be reprecipitated by acidification. No methoxyl groups were present. The neutral equivalent was determined to be 159. This value, coupled with the empirical formula $(C_5H_8O)_x$ as determined from carbon-hydrogen analysis data, indicates the molecular formula to be $C_{10}H_{12}O_2$. This corresponds to the formula for dehydroperilllic acid as given above.

Two derivatives of the above described acid product were prepared. The methyl ester melted at 34° C. to 35° C. and boiled at 104° C. to 106° C. The anilide, prepared by reaction of the acid or of its acyl derivatives with aniline, was a crystalline compound melting at 96° C.

It is apparent that the process of the present invention has manifold advantages. In the first place, it accomplishes the isolation of a pure, well defined organic chemical compound from wood substance. It represents for the first time a commercial process for the production of dehydroperilllic acid. It makes available at relatively low cost a new and useful chemical product, which has many potential applications per se, or as a starting material for the processes of the synthetic chemical industry. Finally and broadly, it represents a successful effort to obtain a useful chemical by-product from a mild-controllable procedure for the fractionation of wood substance.

Having now described my invention and in what manner the same may be used, what I claim as new and desire to protect by Letters Patent is:

1. The process for treating lignocellulose material for the recovery of dehydroperilllic acid and lignin products, comprising treating a lignocellulosic source material for said acid and lignin with an aqueous solution of a basic-acting compound of an alkali metal at a temperature of from about normal room temperature to about the boiling point of said solution at atmospheric pressure and in concentration sufficient to provide not substantially more than about 15 parts by weight of said alkali metal compound per 100 parts of dry lignocellulose material for forming an extracted mass of said material and an aqueous alkaline extract containing dehydroperilllic acid and lignin product, separating the said mass from the said extract, substantially neutralizing said alkaline extract and conditioning it by establishing a salt concentration sufficient to effect

precipitation of a substantial amount of lignin products, separating the precipitated lignin products thereby leaving a residual extract, acidifying the residual extract to a pH value of between 4 and 6 for precipitating dehydroperillie acid and lignin, and separating the thus precipitated dehydroperillie acid from the co-precipitated lignin and acidified lignin-containing extract.

2. The process for treating lignocellulose material for the recovery of dehydroperillie acid and lignin products, comprising treating a source material for said acid and lignin with an aqueous solution of a basic-acting compound of an alkali metal at a temperature of from about normal room temperature to the boiling point of said solution at atmospheric pressure and in concentration sufficient to provide not substantially more than about 15 parts of said alkali compound per 100 parts of dry lignocellulose material for a time period sufficient substantially to exhaust the action of the solution for forming an extracted mass of said material and an aqueous alkaline extract containing dehydroperillie acid and lignin product, separating the said mass from the said extract, substantially neutralizing said alkaline extract and conditioning it by establishing a salt concentration sufficient to effect precipitation of a substantial amount of lignin products, separating the precipitated lignin products thereby leaving a residual neutral extract, acidifying the residual extract to a pH value of between 4 and 6 for precipitating dehydroperillie acid and lignin, and separating the precipitated dehydroperillie acid from any co-precipitated lignin and the acidified lignin-containing extract.

3. The process for treating lignocellulose material for the recovery of dehydroperillie acid and lignin products, comprising treating a source material for said acid and lignin with an aqueous solution of a hydroxide of an alkali metal at a temperature of from about normal room temperature to about the boiling point of said solution at atmospheric pressure and in concentration sufficient to provide not substantially more than about 15 parts of said alkali compound per 100 parts of dry lignocellulose material for forming an extracted mass of said material and an aqueous alkaline extract containing dehydroperillie acid and lignin product, separating the said mass from the said extract, neutralizing the said extract and conditioning it while maintaining it substantially neutral by establishing a salt concentration in a sufficient amount to cause the precipitation of a substantial amount of its lignin product content, separating the precipitated lignin product from the residual solution, acidifying the said residual solution to a pH value of between 4 and 6 for precipitating dehydroperillie acid, and separating the thus precipitated dehydroperillie acid from any co-precipitated lignin and the acidified lignin-containing extract.

4. The process for treating lignocellulose material for the recovery of dehydroperillie acid and lignin products, comprising treating a source material for said acid and lignin products with an aqueous solution of an alkali metal carbonate at a temperature of from about normal room temperature to the boiling point of said solution at atmospheric pressure and in concentration sufficient to provide not substantially more than about 15 parts of said alkali compound per 100 parts of dry lignocellulose material for a time sufficient substantially to exhaust the action of said solution for forming an extracted mass of said material and an aqueous alkaline extract con-

taining dehydroperillie acid and lignin products, separating the said extract from the extracted material, neutralizing the said extract and conditioning it by establishing a salt concentration sufficient to effect the precipitation of a substantial amount of lignin products, separating the precipitated lignin products from the residual neutral solution, acidifying the residual neutral solution to a pH of between 4 and 6 for precipitating dehydroperillie acid, and separating the precipitated dehydroperillie acid from any co-precipitated lignin products and from the residual acidified solution.

5. The process for treating lignocellulose material for the recovery of dehydroperillie acid and lignin products, comprising treating a source material for said acid and lignin products with an aqueous solution of a basic-acting compound of an alkali metal at a temperature of from about normal room temperature to the boiling point of said solution at atmospheric pressure and in concentration sufficient to provide not substantially more than about 15 parts of said alkali compound per 100 parts of dry lignocellulose material for a time sufficient substantially to exhaust the action of the said solution for forming an extracted mass of said material and an aqueous alkaline extract containing dehydroperillie acid and lignin products, separating the said extract from the extracted material, neutralizing the said extract and conditioning it by establishing a salt concentration sufficient to effect the precipitation of a substantial amount of lignin products, separating the precipitated lignin products from the residual neutral solution, acidifying the residual neutral solution to a pH of between 4 and 6 for precipitating additional finely divided lignin product particles and relatively large crystals of dehydroperillie acid, and filtering the resulting aqueous suspension through a filtering means having a mesh size such as to permit the passage of the aqueous medium and of the finely divided lignin product particles but to retain the dehydroperillie acid crystals.

45. 6. A process for the production of dehydroperillie acid and lignin products from wood, which comprises treating comminuted wood which is a source material for said acid and lignin with an aqueous solution of an alkali metal hydroxide at a temperature of from about normal room temperature to the boiling point of said solution at atmospheric pressure and in concentration sufficient to provide not substantially more than about 15 parts of said alkali metal hydroxide per 100 parts of dry wood for a time period sufficient substantially to exhaust the action of the said solution for forming an extracted mass of wood and an aqueous alkaline extract containing dehydroperillie acid and lignin products, separating the said extract from the extracted fiber, substantially neutralizing the said extract and conditioning it by establishing a salt concentration sufficient to effect the precipitation of a substantial amount of lignin products, separating the precipitated lignin products from the said solution, acidifying said neutral solution to a pH value of between about 4 and 6, and separating the thus precipitated dehydroperillie acid from any co-precipitated lignin and from the acidified lignin-containing solution.
